Primary Examiner — Cynthia Underwood(74) *Attorney, Agent, or Firm* — Bacon & Thomas, PLLC(57) **CLAIM**

The ornamental design for a hinge, as shown and described.

DESCRIPTION

FIG. 1 is a front elevational view of a hinge showing my new design;

FIG. 2 is a rear elevational view thereof,

FIG. 3 is a top plan view thereof,

FIG. 4 is a bottom plan view thereof,

FIG. 5 is a right side elevational view thereof,

FIG. 6 is a left side elevational view thereof,

FIG. 7 is a top perspective view thereof,

FIG. 8 is a sectional view thereof, taken along line 8-8 of FIG. 1,

FIG. 9 is a perspective view thereof, shown in its environment of use, the broken lines forming no part of the claim; and,

FIG. 10 is a bottom plan thereof, in a closed position.
